CLAIM

The ornamental design for a hermetic terminal, as shown
and described.

DESCRIPTION

FIG. 1 is a perspective view of a first embodiment of a
hermetic terminal showing my new design;

FIG. 2 is a front view thereof;

FIG. 3 is a rear view thereof;

FIG. 4 is a top view thereof;

FIG. 5 is a bottom view thereof;

FIG. 6 is a right view thereof;

FIG. 7 is a left view thereof;

FIG. 8 is a cross sectional view taken along line **8-8** of FIG.
2;

FIG. 9 is a perspective view of a second embodiment of a
hermetic terminal showing my new design;

FIG. 10 is a front view thereof;

FIG. 11 is a rear view thereof;

FIG. 12 is a top view thereof;

FIG. 13 is a bottom view thereof;

FIG. 14 is a right view thereof;

FIG. 15 is a left view thereof; and,

FIG. 16 is a cross sectional view taken along line **16-16** of
FIG. **10**.

The short-dash broken lines illustrate unclaimed portions of
the hermetic terminal and form no part of the claimed
design. The long-dash and short-dash broken line represents
an unclaimed boundary between the claimed design and
unclaimed portions of the hermetic terminal, and forms no
part of the claimed design.
